CLAIM

The ornamental design for a connection member for a modular support frame, as shown and described.

DESCRIPTION

FIG. 1 is a perspective view of the first embodiment of a connection member for a modular support frame showing our new design;

FIG. 2 is a front view thereof;

FIG. 3 is a rear view thereof;

FIG. 4 is a side view thereof;

FIG. 5 is a second side view thereof;

FIG. 6 is a top view thereof;

FIG. 7 is a bottom view thereof;

FIG. 8 is a perspective view of the second embodiment of a connection member for a modular support frame showing our new design;

FIG. 9 is a front view thereof;

FIG. 10 is a rear view thereof;

FIG. 11 is a side view thereof;

FIG. 12 is a second side view thereof;

FIG. 13 is a top view thereof; and,

FIG. 14 is a bottom view thereof.

The broken lines in the drawings illustrate portions of the connection member for a modular support frame and form no part of the claimed design.

The shade lines in the Figures show contour and not surface ornamentation.
